(57) **CLAIM**

The ornamental design for a race car, as shown and described.

DESCRIPTION

FIG. 1 is a front elevational view of the race car showing my new design;

FIG. 2 is a rear elevational view thereof;

FIG. 3 is a top plan view thereof;

FIG. 4 is a left side elevational, the right side being a mirror image thereof; and,

FIG. 5 is a perspective view thereof.

The bottom surface of the design is not visible during use.
